UNITED STATES PATENT OFFICE.

WILLIAM RAYMOND ALLEN, OF HUTCHINSON, KANSAS.

AUTOMATIC TIMING DEVICE.

1,398,000.

Specification of Letters Patent.

Patented Nov. 22, 1921.

Application filed December 13, 1920. Serial No. 430,361.

To all whom it may concern:

Be it known that I, WILLIAM RAYMOND ALLEN, a citizen of the United States, residing at Hutchinson, in the county of Reno 5 and State of Kansas, have invented certain new and useful Improvements in Automatic Timing Devices, of which the following is a specification.

This invention relates to improvements in 10 timers to be used in connection with internal combustion engines and the principal object of the invention is to provide improved mechanism for automatically governing the time or period when a spark shall occur in 15 the ignition system in each cylinder of the engine, thus making it unnecessary for a retard and advance lever to be used at the drive wheel.

The invention was devised particularly 20 for use in connection with the engine of the Ford automobile but it is obvious that it may be applied to engines of other kinds and types.

A further object of the present invention 25 is to provide improved mechanism which may be substituted for the internal mechanism of the ordinary timer without altering the engine or the engine shaft.

Another object of the invention is to provide 30 simple, inexpensive and durable mechanism which by reason of its simple construction, is not liable to easily get out of order.

With the foregoing objects outlined and with other objects in view which will appear 35 as the description proceeds, the invention consists in the novel features hereinafter described in detail, illustrated in the accompanying drawing and more particularly pointed out in the appended claims.

40 Referring to the drawing:—

Figure 1 is a vertical transverse sectional view of the improved timer.

Fig. 2 is a longitudinal sectional view taken on line 2—2 of Fig. 1.

45 Fig. 3 is a perspective view of the roller carrying member forming part of the present invention.

Fig. 4 is a perspective view of the counter weight lever.

50 Fig. 5 is a perspective view of the cylinder which forms the support for my improved mechanism.

Fig. 6 is a perspective view of the disk to which the counter weight lever is pivoted.

55 Fig. 7 is a side view of the roller.

In the drawing 1 represents an ordinary

timer shaft which in the present instance, is provided with a cylinder 2 having a notch 3 designed to engage a pin 4 extending from the shaft for fixing the cylinder to said shaft 60 and causing the cylinder to rotate with the shaft.

A supporting member such as a disk 5 is fixed to one end of the cylinder by means of a pin 6 which enters a notch 7 in the cylinder and a similar notch 8 in the disk. The disk is provided with an extension 9 having an end 10 which extends parallel to the disk and is apertured, as shown at 11.

A counter weight lever 12 having a hub 70 13 provided with a hole 14, is inserted between the end member 10 and the disk 5, and a pin 15 passes through the aperture 11, the hole 14 and a hole 16 in the disk 5, for securing the lever 12 to the disk. The lever 12 75 is thickened or enlarged, as shown at 17, to provide a counter weight and the outer end of this counterweight is bifurcated, as shown at 18, and the arms of the bifurcated end are apertured, as shown at 19. It will be noted 80 that the lever 12 and its counter weight is located on one side of the timer shaft and on the opposite side a roller carrying lever 20 is arranged.

The lever 20 has one of its ends 21 apertured, as shown at 22, and the end 21 is inserted between the arms 18 to provide a knuckle joint, a pin 23 passing through the apertures 19 and 22 which secures the ends of the levers 12 and 20 together. The knuckle joint prevents the lever 20 from moving to a position where its roller 24 will disengage the track way 25 of the casing 26. The lever 20 is cut away as shown at 27 to provide a seat for the roller 24 and a pin 28 95 passes through apertures in the lever 20 and the roller 24 for securing said roller to the lever 20.

The free ends of said levers 12 and 20 are provided with parallel apertured extremities 29 and 30 between which is located a coiled spring 31, adjusting means 32 being provided for varying the tension of the spring.

The casing 26 is of ordinary construction 105 having an arm 33 for adjusting the position of the contact segments 34 which are counter sunk in the insulated ring 35 and have terminals 36 to receive the wires of the ignition system.

When the shaft 1 rotates in a clockwise direction, it will cause the roller 24 to inter-

mittently contact with the fixed contacts 34 and as the speed of the shaft increases, the counter weight 17 will move outwardly away from the shaft 1 and will advance the 5 roller 24 to cause an advance of the time of spark in the engine cylinders. As the speed of the engine decreases, the spring 31 will draw the roller 24 in a reverse direction and retard the spark. Various adjustments may 10 be made in the time of ignition by properly weighting the part 17 and by suitably adjusting the adjusting means 32.

From the foregoing we believe the construction and operation of our mechanism 15 will be apparent to those skilled in the art, but we may state that the improved mechanism which includes the parts 2, 5, 12, 20 and 31 may be quickly inserted in the ordinary timer in substitution for the internal 20 mechanism now in general use.

Attention is called to the following advantages of the invention. Its working parts are of strong and durable construction throughout and as these parts are few 25 in number, they are not likely to get out of order. There are no additional parts to be applied to a Ford engine in order to attach the improved mechanism. There is no need for a spark lever with the present invention.

30 When applying the mechanism to the timer shaft of a Ford automobile, it is keyed onto the shaft at exactly the same position as the ordinary internal mechanism of the Ford timer, which causes it to start with the 35 shaft at the most retarded position. Hence, after placing the mechanism in position, the spark lever at the steering wheel is placed in the most retarded position and is left there, and after this the improved mechanism will 40 operate at the desired intervals to furnish sparks at all speeds.

In the drawing and description the preferred embodiment of the invention is disclosed but it is obvious that numerous 45 changes and modifications may be made in the construction illustrated without departing from the spirit of the invention as set forth in the claims.

What is claimed and desired to be secured 50 by Letters Patent is:—

1. A timer including a shaft, a supporting

member carried thereby, a counterweighted lever pivotally mounted on said supporting member and movable in a plane perpendicularly to the axis of said shaft, a roller support operatively connected with and actuated in one direction by said counterweight lever, a contact roller carried by the roller support, and means for moving the roller support in a direction opposite to that in which it is moved by said counterweight lever.

2. A timer of the kind defined by claim 1 in which the supporting member includes a cylinder mounted on the shaft and carrying 65 a disk to which the counterweighted lever is connected.

3. A timer of the kind defined by claim 1 in which the counterweighted lever is pivotally connected at an intermediate portion to 70 the supporting member.

4. A timer of the kind defined by claim 1 in which the roller support includes a lever provided at one end with means for pivotally connecting the same to the counterweighted lever, and provided at its opposite end with the means for moving the roller support in a direction opposite to that in which it is moved by said counterweighted lever.

5. A timer of the kind defined by claim 1 in which the roller support includes a curved lever and in which the contact roller is rotatably mounted in an intermediate portion of the last named lever.

6. A timer of the kind defined by claim 1 in which the means for moving the roller support in a direction opposite to that in which it is moved by said counterweighted lever, includes a spring.

7. A timer including a shaft, a disk mounted on said shaft, a counterweighted lever pivotally mounted on said disk and movable in a plane perpendicularly to the axis of said shaft, a roller support lever 95 pivotally connected to one end of said counterweighted lever and carrying a contact roller at an intermediate portion of the same, and a spring between the roller support lever and the counterweighted lever.

In testimony whereof I affix my signature.

WILLIAM RAYMOND ALLEN.
